UNITED STATES PATENT OFFICE

FRANCIS GEORGE DARLINGTON, OF SAN FRANCISCO, CALIFORNIA

SWITCH-BOX PLATE COVER

Application filed October 25, 1927. Serial No. 228,652.

This invention relates to a switch box cover or plate, and its object is to furnish, at small cost and trouble an ornamental cover for a switch box plate which, by the fact that it can be manufactured in any number of colors, shades, shapes and designs and can be put in place with a minimum of labor and knowledge, will meet the needs and requirements of the greatest number of people.

10 An object of the design is to enable anyone to easily and quickly install the cover and also to remove one or more of the superimposed sheets of fabricated material, in order to have or to install a new, clean or 15 different sheet. Other objects of the invention will be apparent as the description proceeds.

An embodiment of the invention is shown in the accompanying drawings in which the 20 same reference numeral is applied to the same portion throughout the several figures of the drawing and of which there may be modifications.

Figure 1 is a plan of the plate before pad 25 of sheets is attached.

Figure 2 is a cross-section along the center line of the plate longways, with pad attached.

Figure 3 is a cross-section of the plate across the plate at center with pad attached.

30 Figure 4 is a plan of the plate with one type of pad attached.

Figure 5 is a side elevation of plate with pad attached.

Figure 6 is an end elevation of plate with 35 pad attached.

Figure 7 shows the clips #4 snapped onto screwhead in attaching plate to switch box.

Figure 8 is a plan of a switch box plate with cover attached.

40 Figure 9 is a cross-section along the centerline longways showing cover attached to switch box plate.

Figure 10 is a cross-section along the centerline crossways showing cover attached 45 to switch box plate.

Figure 11 is a plan of cover showing under side with area treated with adhesive material.

Figure 12 is a plan of a cover of a different shape than the plate but following the general 50 outline of the plate.

This cover is of the type which can be attached to the switch box plate by moistening the adhesive material on the back side of the cover and pressing upon the plate, and which itself and any of the superimposed sheets 55 can be removed as desired.

Sheet #5 is a basic sheet of fabricated material, perforated to expose and operate the switch box mechanism, shaped to fit the general outline of the switch box plate, having 60 an area of the back treated with adhesive material to allow of being attached to switch box plate, and on top of which a pad of sheets of fabricated material can be attached.

Pad #1 is a number of sheets of fabricated 65 material perforated to expose and operate switch control mechanism, and fastened together on the edges with an adhesive material, a small section being left clean to allow of grasping in order to loosen each sheet when 70 desired, the whole to be attached to the basic cover sheet #5 by above mentioned adhesive material.

Plate #2 is made of metal pressed into 75 shape to obtain projecting edges in order to obtain a tight fit against wall or block carrying switch box, perforated by hole #3 and cut and shaped to form slips #4.

Hole or holes #3 is cut in cover sheet 5 and 80 pad 1 to fit over standard push button, straight toggle service connection, or other type of switch box cover or plate, in order to expose and operate the switch box mechanism.

Clips #4 are two pairs of shaped metal 85 pieces cut and bent into position to engage screwheads in attaching to switch box.

The edges of pad, also edges of hole are glued together with the exception of one corner or a special clip section which is left 90 free to allow of getting hold of sheet to tear sheet loose when desired.

The shape of the plate #2 is not absolutely set as it can be varied to suit desire, but the hole #3 and clips #4 are determined by the 95 type of switch box it is desired to cover. The clips #4 are used to avoid the unsightly attaching screws and secure ease of setting up and adjusting of portion of plate assembly, 100 allowing of setting hole #3 over switch op-

erating mechanism and pressing clips #4 over screwheads, also slight vertical movement to prevent binding on switch operating mechanism. Area #6 is a section of the back of cover sheet 5 immediately adjacent to hole or holes 3, on which an adhesive material is placed to allow of attaching cover sheet 5 to the switch plate by moistening and pressing against plate, at the same time fitting hole or holes 3 to the proper position.

Having thus described my invention, what I desire to secure by Letters Patent of the United States is as follows, but modification may be made in carrying out the invention as shown in the drawings and in the above particularly described form thereof, within the preview of the annexed claims:

1. A switch box plate cover of the class described, a cover sheet consisting of one sheet of fabricated material shaped to fit the general outline of the switch box plate and having an area on the back treated with adhesive material, a pad of sheets of fabricated material fastened together and to cover sheet, both cover sheet and pad being perforated to expose and operate the switch box mechanism.

2. A switch box plate cover of the class described, consisting of a pad of sheets of fabricated material, each sheet of which is perforated to allow of exposure and operation of the switch box mechanism, said sheets being removable one or more at a time and being attached to a cover sheet perforated by a hole or holes of a size and shape to allow of exposure and operation of switch box mechanism, and said sheet to be shaped to the general outline of the switch box plate and to have an area on the back treated with an adhesive material to allow of being attached to the switch box plate.

3. A switch box plate cover of the class described, consisting of a cover sheet of fabricated material perforated by a hole of a size and shape to allow of exposure and operation of the switch box mechanism said sheet to be shaped to the general outline of the switch box plate and to be treated on the back with an adhesive material to allow of being attached to switch box plate.

4. A switch box plate cover of the class described, consisting of a pad of sheets of fabricated material so attached to each other as to allow of being separated one or more at a time, said pad to be perforated by a hole or holes of a size or shape to allow of operating the switch mechanism, and having an area on the back of the bottom sheet of the pad treated with adhesive material to allow of being attached to the switch box plate.

Signed at the city and county of San Francisco, State of California, on this 20th day of October, 1927.

FRANCIS GEORGE DARLINGTON.
